UNITED STATES PATENT OFFICE.

ADAM KAUFMAN, OF MILWAUKEE, WISCONSIN, ASSIGNOR TO RES MANUFACTURING COMPANY, OF MILWAUKEE, WISCONSIN.

BACK FOR VESSELS.

1,017,102.

Specification of Letters Patent. Patented Feb. 13, 1912.

Application filed May 9, 1911. Serial No. 626,120.

To all whom it may concern:

Be it known that I, ADAM KAUFMAN, a citizen of the United States, and resident of Milwaukee, in the county of Milwaukee and 5 State of Wisconsin, have invented certain new and useful Improvements in Racks for Vessels; and I do hereby declare that the following is a full, clear, and exact description thereof.

10 The object of this invention is to provide a simple, rigid and sanitary rack for holding receptacles of various kinds, such, for instance, as bottles, glasses or the like, the invention consisting in certain peculiarities 15 of construction and combination of parts hereinafter set forth with reference to the accompanying drawings and subsequently claimed.

In the drawings Figure 1 represents a 20 face view of the rack embodying the features of my invention, the rack being illustrated with a series of six holders only; Fig. 2, an enlarged longitudinal sectional view of one of the holders as indicated by 25 line 2—2 of Fig. 1; Fig. 3, a detail plan view of one of the holders, shown attached to a member of a skeleton frame, said member being in section, and Fig. 4 a plan view of a blank from which the holders are 30 formed.

Referring by characters to the drawings, 1, 1, represent longitudinal bars connected by transverse bars 2 and an intermediate bar 2^a, the transverse and longitudinal bars 35 constituting a supporting frame for a series of holders.

As best shown in Fig. 4, each holder is 40 formed from a single blank of spring metal having a circular foot 3, a backbone 4, lateral spring-arms 5, which extend from the backbone, and a neck portion 6, which projects from the arms and is alined with the backbone 4. The foot 3 of the holder blank is bent at right angles to the backbone portion 45 and the spring-arms 5 are bowed out from said backbone so as to form segments of a circle with the axis thereof slightly offset from the axis of the circular boot 3, the arms being terminated to form a contracted 50 throat therebetween with the terminal points of the arms flared in scroll formation so as to present unobstructed ends at the throat, whereby a vessel of the proper dimensions 55 may be inserted therebetween. The upper ends of the longitudinal bars 1 are provided

with key-hole apertures 7 for the purpose of suspending the rack upon pins arranged conveniently therefor.

As shown in Fig. 1, the transverse bar 2 and longitudinal bars 1 are connected by 60 an open gromet which is arranged to pass through the apertures therein and also an aperture in the head 6 of one of the holders, there being a similar gromet for securing the holder adjacent to its foot portion 3. 65 This latter gromet passes through an aperture in the backbone and a corresponding aperture in the longitudinal bar 1.

As best shown in the enlarged detail view, Fig. 2, the backbone 4 of each holder is offset as indicated at 4^a, for a portion of its distance which is approximately equal to the width of its arms, this offset being provided for the purpose of elevating the surface of the backbone from the plane of the 75 supporting frame of the holders, whereby a vessel that is inserted within the holder will not contact with the adjacent parts of the frame, this being especially desirable wherein vessels are placed within the holder 80 having upwardly flared or tapered walls. By utilizing this offset portion as a face for the vessel to seat against, it will be seen that the same will be grasped by the spring-arms 85 and thus held by a three-point contact, the vessel being supported upon the foot 3 as shown.

By constructing a rack in the manner described, it will be seen that a simple and sanitary article is formed, being 90 entirely of metal, and by constructing the holders of a single blank the cost of manufacture is materially reduced, while its effectiveness for the purpose set forth is not impaired.

I claim:

1. A rack comprising a skeleton frame having vertical and transverse bars, a series of holders secured to the vertical bars, each holder being formed from a single blank comprising a circular foot portion and a 100 backbone extending therefrom, the circular foot portion being at right angles to the backbone, oppositely disposed circular arms radiating from the backbone and terminating to form an open throat therebetween, a 105 neck extending from the backbone, and securing means connecting the backbone and neck to said vertical arm.

2. A rack comprising a skeleton frame having vertical and transverse bars, a series 110

of holders secured to the vertical bars, each holder being formed from a single blank comprising a circular foot portion and a backbone extending therefrom, the circular 5 foot portion being at right angles to the backbone, oppositely disposed circular arms radiating from the backbone and terminating to form an open throat therebetween, an offset portion upon the backbone approximately at the point of junction between 10 the arms of said backbone, a neck extending

from the backbone, and securing means connecting the backbone and neck to said vertical arm.

In testimony that I claim the foregoing I 15 have hereunto set my hand at Milwaukee in the county of Milwaukee and State of Wisconsin in the presence of two witnesses.

ADAM KAUFMAN.

Witnesses:

MAY DOWNEY,
Geo. W. YOUNG.
